(57) **CLAIM**

The ornamental design for a gel container, as shown and described.

DESCRIPTION

FIG. 1 is a front, top and left side perspective view of a gel container;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a bottom plan view thereof; and,

FIG. 8 is a front, bottom and left side perspective view of the gel container.

The broken lines shown in the Figures are included to show unclaimed subject matter only and form no part of the claimed design.

1 Claim, 4 Drawing Sheets
